DESIGN FOR A SUPPORT FOR FLORAL DISPLAYS

Clarence J. White, Peoria, Ill.

Application November 23, 1937, Serial No. 73,131

Term of patent 14 years

To all whom it may concern:

Be it known that I, Clarence J. White, a citizen of the United States, residing at Peoria, in the county of Peoria and State of Illinois, have invented a new, original, and ornamental Design for Supports for Floral Displays, of which the following is a specification, reference being had to the accompanying drawing forming a part thereof,

Fig. 1 is a perspective view of a support for floral displays, showing my new design; and

Fig. 2 is an enlarged detail view of one of the prongs shown in Fig. 1.

I claim:

The ornamental design for a support for floral displays, as shown.

CLARENCE J. WHITE,
